UNITED STATES PATENT OFFICE

LEWIS K. LARRISON, OF WHARTON, NEW JERSEY

PLUMBING DEVICE

Application filed November 12, 1927. Serial No. 232,894.

This invention aims to provide a novel device whereby a builder may erect means for determining the corners of a building, and whereby he may have at his command a means by which he can be assured that the courses of brick, tile or the like, are arranged horizontally.

In the drawings:—

Figure 1 shows in elevation, a device constructed in accordance with the invention;

Figure 2 is an elevation wherein the structure is viewed at right angles to the showing of Figure 1;

Figure 3 is a cross section on the line 3—3 of Figure 1;

Figure 4 is a perspective view showing one of the posts, parts being broken away;

Figure 5 is a section taken on the line 5—5 of Figure 1, remote parts being omitted;

Figure 6 is a cross section on the line 6—6 of Figure 1.

In carrying out the invention, there are provided four posts, but since the posts are of like construction, the description will proceed in the singular number as to the posts. Each post 1, then, may be made of any suitable material. Each post 1 is calibrated longitudinally, as shown at 2, the units of calibration being large. The post 1 has an outstanding upper arm 3 and an outstanding lower arm 4. There is an opening 5 in the arm 3, and the arm 4 is provided with an opening 6. The openings 5 and 6 are the same distance from the longitudinal center of the post 1. The numeral 7 marks a plumb line. The upper end of the plumbline 7 is mounted in the opening 5 of the arm 3. A bob 8 is mounted on the lower end of the plumbline 7. The bob 8 cooperates with the opening 6 in the lower arm 4 to show when the post 1 is vertically disposed. The post 1 may be provided with a level 9, whereby the post may be used, if desired, to lay horizontals.

The numeral 10 marks a foot, having upstanding ears 11, between which the lower end of the post 1 is disposed. A pivot element 12, such as a bolt, is mounted in the ears 11 and extends through an opening 14 formed in the post 1 near to the lower end of

the post. A piece of board, marked by the numeral 15, is mounted on the ground 16, or on any part of the building which may be accessible. By means of securing elements 17, the foot 10 is secured to the member 15. A rider 18, in the form of a U-shaped member, is mounted on the post 1 for adjustment longitudinally of the post. Oppositely disposed clamp screws 19 and 20 are threaded into the arms of the rider 18 and are adapted to bind upon or extend into the post 1. A third clamp screw 21 is mounted in the end of the rider 18 and is disposed at right angles to the clamp screws 19 and 20. Braces 22 and 23 are provided, and are located at right angles to each other. The brace 23 is held on the rider 18 by the clamp screw 21, and the clamp screw 19 holds the brace 22 on the rider. For the sake of adjustment, the upper ends of the braces 22 and 23 are supplied with elongated slots 24 in which the bolts 19 and 21, respectively, are mounted. At their lower ends, the inclined braces 22 and 23 are provided with enlarged feet 25 having openings 26 adapted to receive stakes 27 or other fastening devices, whereby the feet may be connected to the ground 16 or to anything else that is available. Owing to the fact that the braces 22 and 23 have slots 24, and because the anchorage at 27 is not absolutely immovable, and because the post 1 has some movement on the bolt 12, the post 1 may be swung around in any desired direction, enough to plumb it, by means of the line 7 and the bob 8, and when the post 1 is in a truly vertical position, as nearly as the same can be determined within practical limits, the screws 21 and 19 are tightened up, and, then, the braces 22 and 23 will hold the post 21 in a vertical position at the corner of the wall 28 which is to be built.

A loop-shaped slide 28 is mounted for adjustment on the post 1, longitudinally of the post. The slide 28 has an off-set socket 29 in which is mounted a rule 30, the calibrations of the rule being finer than the calibrations 2 of the post 1. A set screw 31 is threaded into the socket 29 of the slide 28 and serves to press the rule 30 against the post 1 for the double purpose of holding the

rule 30 in any position to which it may have been adjusted longitudinally, and of holding the socket 29 in any position to which it may have been adjusted lengthwise of the post 1. The slide 28 has a fastening device 32, such as a hook, to which may be connected one end of a line 33, shown in Figure 3, the line 33 being extended horizontally to another slide 28 on a post corresponding to the post 1. The position of the slides 28, considered vertically, may be regulated approximately by means of the large calibrations 2 on the post 1, and, then, the positions of the slides 28 can be determined more accurately by using the rules 30, with small calibrations, in connection with the marks shown at 2, in a way which will be obvious when Figure 1 of the drawings is noted.

It will be obvious that the device forming the subject matter of this application may be used not only to keep the corner of the wall vertical, but it may be used, also, to keep all of the bricks, tiles, or other building elements, in a horizontal position in any particular course, the slides 28 being moved upwardly and being re-set, as one course after another is laid.

What is claimed is:—

1. In a device of the class described, a substantially vertical post, a plumbing device carried by the post, a foot, means for connecting the lower end of the post pivotally with the foot, a rider adjustable on the post longitudinally thereof, means for holding the rider in adjusted positions longitudinally of the post, braces inclined with respect to the post, means for connecting the upper ends of the braces adjustably with the rider to permit plumbing of the post, and means anchoring the lower ends of the braces.

2. In a device of the class described, a substantially vertical post, means for mounting the post at its lower end for swinging movement, means carried by the post for plumbing the post, adjustable means for holding the post in plumb position, a slide adjustable longitudinally of the post and provided with means for holding a horizontal line, a rule within the slide and adjustable longitudinally in the slide, and a clamping device carried by the slide and engaging the rule to press the rule against the post and to hold both the rule and the slide in adjusted positions, the post having calibrations wherewith the rule cooperates.

In testimony that I claim the foregoing as my own, I have hereto affixed my signature.

LEWIS K. LARRISON.
